UNITED STATES PATENT OFFICE

NATHAN H. SUREN, OF NEEDHAM, MASSACHUSETTS, ASSIGNOR TO GAMEWELL FIRE ALARM TELEGRAPH COMPANY, OF NEW YORK, N. Y., A CORPORATION OF NEW YORK.

FIRE-ALARM-TELEGRAPH SYSTEM.

1,145,941.

Specification of Letters Patent. Patented July 13, 1915.

Application filed February 2, 1914. Serial No. 815,970.

To all whom it may concern:

Be it known that I, NATHAN H. SUREN, a citizen of the United States, residing at Needham, in the county of Norfolk and 5 State of Massachusetts, have invented an Improvement in Fire-Alarm-Telegraph Systems, of which the following is a specification.

This invention relates to fire-alarm telegraph systems of that type wherein one or more fire alarm boxes are connected with a main circuit having a signal-transmitter normally biased to circuit-closing position and arranged to open the circuit for periods 10 of time of different length in the transmission of a signal, as for instance, those breaks in the circuit representing the number are of short duration, those representing the interval of time between number groups are 15 of longer duration, and those representing the interval of time between rounds of a number are of still longer duration, and one or more receiving-instruments are employed to receive the signals, such for instance as 20 a signal-recorder, register, whistle, horn or gong, which receiving-instrument is included in a local-circuit and controlled by a relay electrically connected with the controlling-circuit, and which is responsive to 25 the operation of the signal-transmitter. Such form of apparatus is now in common use and the relay and the receiving-instruments controlled by it are variably responsive, according to the variable intervals of 30 time the controlling-circuit is opened by the signal-transmitter, and as a result the blasts of the whistle and horn and the dashes of the recorder are of varying duration.

Heretofore means have been arranged on 40 certain forms of signal-receiving instruments, such for instance as a whistle and signal-recorder by which the blasts of the whistle and dashes of the recorder are caused to be made of uniform length regardless of the length of the signal-impulses, 45 but separate means are provided for each receiving-instrument and their operation is solely in connection with the particular receiving-instrument with which they are associated.

This invention has for its object the provision of means associated with the controlling-circuit, and arranged to control one or more local-circuits containing any number or kind of signal-receiving instruments,

which means is constructed and arranged to close the local-circuit or circuits upon the occurrence of any breaks of the controlling-circuit and to open said local-circuit or circuits at the termination of those breaks 60 which are of shorter duration than a predetermined period or lapse of time, and to open said local-circuit or circuits at the end of such period of time in case the breaks continue for a longer period of time. Such 65 means permits the closing and subsequent opening of the local-circuit or circuits at the end of a predetermined period of time upon the occurrence of breaks of long duration produced by the signal-transmitter, 70 and the closing and subsequent opening of the local-circuit or circuits in correspondence with breaks of short duration produced by the signal-transmitter.

In carrying out my invention I may employ a relay, such for instance as shown in my application No. 747,322, filed February 10, 1913, which is associated with the controlling-circuit and is controlled by the signal-transmitter and which in turn controls 80 the local-circuit or circuits and signal-receiving-instruments controlled by said local-circuit or circuits, but as I am the first to provide any means associated with the controlling-circuit and controlled by a signal- 85 transmitter during the transmission of a signal for controlling a local-circuit or circuits whereby these results may be accomplished, I deem my invention to be of broad scope and hence not limited to this particular means.

Figure 1 is a diagram representing in conventional form a fire-alarm telegraph system embodying this invention. Fig. 2 is a side view of a relay such as may be employed. Fig. 3 is a plan view of the relay shown in Fig. 2. Fig. 4 is a vertical section of the relay taken on the dotted line 4-4, Fig. 2. Fig. 5 is a fragmentary side-elevation illustrating the position of the parts at 95 the moment when the circuit through the relay is broken and its contact-members are in engagement. Fig. 6 is a view similar to Fig. 5 illustrating the position of the parts when the contact-members are separated by 100 the actuation of the spring, the circuit through the relay being still broken, as upon the occurrence of a break in the controlling-circuit of long duration.

125 represents a signal-wheel, and 126, 127 110

a signaling-key or other form of circuit-controller adapted to be operated by the signal-wheel, and herein referred to as the signal-transmitter, and 128 the non-interference magnet of an ordinary fire-alarm box; and 130, 130 represent other like fire-alarm boxes, all connected in any usual or suitable manner in a main or controlling-circuit 131, including a battery 132 or other current-supplying means.

140 represents a local-circuit containing or having electrically connected with it in any usual or suitable manner any suitable form of signal-receiving instruments, such 15 as a signal-recorder, register, whistle, horn, gong and the like. A signal-recorder 141 and a horn 142, are here shown diagrammatically merely illustrating some of the many forms of signal-receiving-instruments 20 which may be employed. 38 and 39, represent a pair of contact-members connected with said local-circuit which are adapted to be engaged by a contact-member 35, to close said local-circuit and thereby cause the signal-receiving instrument or instruments 25 therein to respond, or in lieu thereof any other form of circuit-controller may be employed.

In Figs. 2 to 6, a relay is shown wherein 30 10 represents a pair of electromagnet-coils which are electrically connected together and to binding-posts 12, 14, mounted upon an insulating base 15, to which the controlling-circuit 131 is connected. An armature 35 16 coöperates with the coils 10, and is carried by an arm 18, fast upon a pivot-shaft 20, journaled in conical recesses formed in screws 22, threaded through ears 24 provided at the opposite ends of a plate 26, said plate being mounted upon the upper ends of the coils 10, or otherwise supported. Depending from the shaft 20 is an arm 28, which is bifurcated at its lower portion and carries a transverse bar 30. The bar 30 is 40 provided at each end with a sleeve 31, 32, insulated therefrom by an insulating bushing 34, said sleeves carrying platinum contact-strips 35, 36, respectively. The bar 30 with its contacts constitutes the movable contact-member. As here shown the contact-strip 35 is adapted to engage stationary contact-members 38, 39, and the contact-strip 36 is adapted to engage stationary contact-members 40, 41. The members 39 50 and 41 are connected with binding-posts 44 and 45, respectively, and the members 38 and 40 are connected to binding-posts 46 and 48, by conductors 49, 50, respectively, passing along the under side of the base 15. Thus, as here shown, said movable contact-member is arranged to control two local or 60 relay-circuits, but any other number of local or relay-circuits may be controlled by it, as may be required. A retractile-spring 52 is connected at its upper end to a screw 54,

which projects laterally from the upper end of the arm 28, and also acts as a regulating adjustment by lengthening and shortening, and the lower end of said spring is connected to an ear 56, which projects laterally 70 from a lever 58, fulcrumed in a slotted post 60 mounted upon a ledge 62, which projects upwardly from the base 15. When the magnet-coils 10 are energized, as shown in Fig. 1, the armature 16 is attracted, and the movable contact-member 30 is swung away from the stationary contact-members, and the spring 52 is placed under tension. When the magnet-coils 10 are deenergized, the armature 16 is permitted to retract under the action of the spring 52, and the arm 28 with its transverse bar 30 and contact-members is swung inward, so that the contact-strips or members 35, 36 engage their co-operating stationary contact-members, 38, 80 39, and 40, 41, respectively, to close the local or relay-circuits. In order to control the length of time during which the contact-members 35, 36, are in circuit-closing position, and consequently regulate the length 85 of the blasts of the whistle and horn, as well as the dashes of the recording-instrument, a timed-actuating device is provided for said contact-members which will now be 90 described.

A latch 70 is loosely mounted on the rod 30, and rests upon and is slidable along the bottom of the slot 71, in the post 60. The end 72 of the latch is adapted to be engaged by a finger 74, which projects downwardly 100 from the lever 58. A finger 76 projects diagonally upward from the lever 58, and is adapted to be engaged by a finger 78, which projects laterally from the arm 28, when the armature 16 is in attracted position, thereby holding the lever 58 in elevated position with the timed-actuating device set in condition to operate.

An escape-wheel 80 is affixed to a shaft 82, journaled at its ends in conical sockets 110 formed in the ends of screws 84, which are threaded through the side-arms 86 of a yoke 88, mounted upon an insulating ledge 90, which projects upwardly from the base 15. A toothed pinion or ratchet-wheel 92 115 is also affixed to the shaft 82, and is engaged by a toothed pawl 94 pivoted to the end of the lever 58. This pawl is held in engagement with said ratchet-wheel by a coiled spring 96, connected at one end to said pawl 120 and at its other end to said lever. When the lever 58 is swung downwardly by the spring 52, upon retraction of the armature 16, and removal of the prop 78, the pawl 94 causes the ratchet-wheel 92 to rotate, and with it the escape-wheel 80. The speed of rotation of the escape-wheel 80 is controlled by a pallet 98, secured to a shaft 100, journaled at its ends in conical sockets formed 125 in the ends of screws 102, which are thread- 130

ed through the side-arms 86. A pair of weights 104 are adjustably mounted on arms 106, which are affixed to and project radially from the shaft 100. By adjusting these 5 weights toward or from their center of oscillation, the rapidity of oscillation of the pallet 98 may be varied and consequently the speed of rotation of the escape-wheel 80 and shaft 82. The speed of rotation of the 10 escape-wheel 80 determines the speed of the downward movement of the pawl 94 and lever 58. During downward movement of the lever 58 its finger 74 engages and moves longitudinally the latch 70, and thereby positively moves the movable contact-member 15 out of engagement with the stationary contact-members, but the time consumed in thus moving the movable contact-member is determined by the speed of downward 20 movement of the lever 58.

When the circuit through the magnet-coils 10 is closed by the signal-transmitter the armature 16 is attracted; the finger 78 engages the finger 76, and raises the lever 25 58, and with it the pawl 94; the spring 52 is placed under increased tension; the movable contact-member is moved away from the stationary contact-members, and the end 72 of the latch 70 is disengaged from the 30 finger 74. This is the normal position of the parts, as shown in Fig. 1, the controlling-circuit being closed. When the circuit through the magnet-coils 10 is broken, the first action of the spring 52 is to retract the 35 armature 16, as shown in Fig. 4, and to swing the contact-members 35, 36 into engagement with the stationary contact-members 38, 39, and 40, 41, respectively, to close the local or relay-circuits, and also to bring 40 the end of the latch 70 into engagement with the finger 74. Thereupon the timed-actuating-device immediately commences to operate, that is to say, the spring 52 causes the lever 58 to move downward and there- 45 by actuate the timing-mechanism which is driven by the pawl 94; and as said lever 58 is lowered the finger 74 pushes the latch 70 toward the right, thereby moving the contact-members 35 and 36 away from their 50 fellow members to open the local or relay-circuits, and the armature 16 is moved slightly nearer the poles of the magnet, shown in Fig. 5, where it remains until attracted upon energization of the magnet- 55 coils, when said operation may be repeated. Upon breaks of the controlling-circuit of the relay of long duration, that is to say, of as long or longer duration than the predetermined time of movement of the timed ac- 60 tuating-device the movable contact-member will be positively moved to disengage its fellow members, thereby closing and subsequently opening the local or relay-circuit or circuits at the end of a predetermined period 65 of time. Upon breaks of said controlling-

circuit of short duration, that is to say, of shorter duration than the predetermined time of movement of the timed actuating-device, the movable contact-member will be positively moved but a short distance by 70 the actuating-spring 52 before the armature 16 is again attracted, whereupon the movable contact-member is positively moved out of engagement with its fellow members and the lever 58 is raised and returned to normal elevated position quickly by the finger 78 engaging the finger 76 and lifting said lever, so that the local or relay-circuit or circuits are closed and subsequently opened 75 in accordance with or for periods of time 80 coextensive with the length of the breaks of short duration.

I claim:—

1. In a fire alarm telegraph system, the combination of a controlling circuit, a signal transmitter arranged to break the controlling circuit for periods of time of two or more different lengths in the transmission of a signal, a local circuit including a signal receiving instrument, a contact member 85 for closing said local circuit, and means associated with the controlling circuit and responsive to said signal transmitter to operate the contact member to close the local circuit upon the recurrence of any break in the controlling circuit, said means being arranged to subsequently operate the contact member to open said local circuit at the end of a predetermined period of time, 90 upon the recurrence of a break in the controlling circuit which is of as long or of longer duration than said predetermined period of time, and to operate said contact member to open said local circuit upon the 95 termination of a break in the controlling 100 circuit which is of shorter duration than the aforesaid predetermined period of time.

2. In a fire alarm telegraph system, a signal transmitter, a controlling circuit governed thereby, a local circuit including a signal receiving instrument, a contact member governing the local circuit, electro-magnetically operated means responsive to the circuit breaks of the signal transmitter and directly operating the contact member, and 110 means operated by said electro-magnetic means for operating the contact member independently of said electro-magnetic means.

3. A fire alarm telegraph system, including a signaling circuit, a contact member therefor, electro-magnetic means for operating the contact member, and means governed by said electro-magnetic means for operating the contact member to break the local circuit independently of the operation 125 of said electro-magnetic means.

4. A fire alarm telegraph system including a circuit, a contact member for opening and closing the circuit, electro-magnetic means responsive to controlling circuit im- 130

pulses operating the contact member to open and close the circuit, and additional mechanical means operated by the electro-magnetic means for controlling said contact member.

5. In a fire alarm telegraph system, a signal transmitter, a controlling circuit governed thereby, a local circuit including a signal, a contact member for the local circuit, electro-magnetically operated means responsive to all circuit impulses of the signal transmitter and operating the contact member to open and close the circuit, and additional means operated by said electro-magnetic means for directly controlling the contact member between circuit breaks of the signal transmitter of greater length than a predetermined period.

6. In a fire alarm telegraph system, a local circuit including a signal receiving instrument, a contact member for opening and closing said circuit, electro-magnetic means responsive to an independent circuit control and operating the contact member to open and close said local circuit, and additional means operated by said electro-magnetic means for operating the contact member in one direction under conditions of non-action of the electro-magnetic means for a predetermined period.

7. A fire alarm telegraph system including a local circuit for energizing a signal instrument, a contact member for opening and closing said circuit, electro-magnetic means responsive to an independent circuit control and operating the contact member to open and close said local circuit, and additional means operated by the electro-magnetic means and having direct operative influence upon the contact member following a predetermined period of time.

8. In a fire alarm telegraph system, a local circuit, a controlling circuit, electro-magnetic means actuated in both making and breaking the controlling circuit, a member directly actuated by the electro-magnetic means in all responses to said means under the influence of the controlling circuit, said member controlling the local circuit, and an independent element actuated by the member in a particular operation of the electro-magnetic means and in turn actuating said member to control the local circuit independently of the electro-magnetic means.

55. 9. In a fire alarm telegraph system, a local circuit, a contact member therefor, an elec-

tro-magnet responsive to an independent circuit control and directly operating the contact member to both open and close the local circuit, and a time device set for operation by the electro-magnet and operating the contact member to open the local circuit following a predetermined interval of time.

10. In a fire alarm telegraph system, a local circuit, a contact member for opening and closing said circuit, an electro-magnet responsive to an independent circuit control and directly operating said contact member in both directions, a mechanical timing device actuating the contact member to open the local circuit at the limit of operation of said timing device, and means actuated by the electro-magnet for setting the timing device for operation.

11. In a fire alarm telegraph system, a local circuit, a contact member for opening and closing said circuit, an electro-magnet responsive to an independent circuit control and directly operating said contact member in both directions, a mechanical timing device actuating the contact member to open the local circuit at the limit of operation of said timing device, and means actuated by the electro-magnet for setting the timing device for operation, said means being operatively actuated by the electro-magnet in that operation of the latter to move the contact member to open the local circuit.

12. In a fire alarm telegraph system, a local circuit, a contact member to open and close said circuit, a mechanical timer actuating the contact member to open the local circuit at the limit of operative movement of said timer, and an electro-magnet responsive to an independent circuit control and directly operating the contact member to both open and close the local circuit, and means actuated by the electro-magnet in its movement to open the local circuit to set the timer for operation, whereby the timer is set at each local circuit opening movement of the electro-magnet to compel a full time operation of the timer and an opening of the local circuit thereby following a circuit control operation of the electro-magnet.

In testimony whereof, I have signed my name to this specification, in the presence of two subscribing witnesses.

NATHAN H. SUREN.
